UNITED STATES PATENT OFFICE.

RALPH R. LEFFLER, OF CLEVELAND, OHIO, ASSIGNOR TO THE HYDRAULIC PRESSED STEEL COMPANY, OF CLEVELAND, OHIO, A CORPORATION OF OHIO.

SUPPORT FOR CONCRETE-FORMS.

1,388,273.

Specification of Letters Patent. Patented Aug. 23, 1921.

Application filed November 21, 1919. Serial No. 339,715.

To all whom it may concern:

Be it known that I, RALPH R. LEFFLER, a citizen of the United States, residing at Cleveland, in the county of Cuyahoga and 5 State of Ohio, have invented a certain new and useful Improvement in Supports for Concrete-Forms, of which the following is a full, clear, and exact description, reference being had to the accompanying drawings.

10 This invention relates generally to concrete forms and more particularly to the improved means for supporting the same, the object being to provide a simple and easily operated supporting device by means of 15 which the form can be held in its proper position during the preliminary settling and hardening of the cement and easily removed without removing the main supports.

With these objects in view the invention 20 consists in the novel features of construction and in the manner of combining or arranging them, all of which will be fully described hereinafter and set forth in the appended claims.

25 In the drawings forming a part of this specification, Figure 1 is a sectional perspective view illustrating one embodiment of my invention; Fig. 2 is an elevation partly in section illustrating the adjustability of the 30 supporting arms; Fig. 3 is a detail perspective view of the supporting arm and Fig. 4 is a detail perspective view of the stirrup to which said arm is attached.

In carrying out the invention I employ 35 sheet metal forms A, which may be arched as shown or flat if preferred. The side edges of these pans are formed with horizontal flanges A' and depending vertical flanges A'', and the forms are arranged in pairs in par- 40 allel order as shown; and resting upon the flanges A' is a filler plate B carried by a wooden strip C, said wooden strip resting upon the upper edge of a joist D which may be supported in any suitable manner.

45 Sheet metal stirrups E are arranged upon the joist D at suitable intervals said stirrups carrying the supporting arms F, one at each side thereof, and which in turn are brought into supporting engagement with the edges 50 of the forms. When the supporting arms are elevated and fastened they are in engagement with and support the forms or pans, and when lowered they are clear of the

edges of the forms or pans and consequently said forms or pans can be removed.

55 Each leg of the stirrup E has inverted key-hole slots E' and E'' cut therein, and each leg also has a square opening E''' cut therein adjacent the lower end thereof. The stirrup E as before stated is placed at suitable intervals along the joist D and is rigidly connected thereto by nails or bolts G which pass through the lower ends of the stirrups into the said stringers, spacing blocks G' being interposed between said ends and the joist in order to space the legs of the stirrup away from the sides of the joist to permit the movements of the parts of the supporting arm and locking lever.

60 The supporting arm F is made of sheet 70 metal, bent centrally to provide two parallel members essentially triangular in shape and the inner edges of said members are formed at one point into a head F' which is adapted to be inserted into the opening E' in the stirrup, and between the lower ends of the parallel members there is pivoted a locking lever H having a hooked end H' which is adapted to enter the opening E'', and in some 65 instances the opening E''', as will be more 75 explained hereinafter.

75 A depending latch I is pivoted at I' be- 80 tween the members of the supporting arm at their upper outer ends, said latch having an opening I'' in the lower end thereof which is 85 adapted to receive and engage the outer end of a locking lever H. The upper end of the latch is turned over the pivotal connection and is somewhat enlarged as shown at I''' in 90 order to prevent dislocation.

95 The upper end of the supporting arm is shouldered as shown at F'', and is also pro- 100 vided with parallel slots F''. When the sup- porting arm is used in connection with the form or pan herein shown, the edge of said pan rests upon the supporting arm and the depending flange A'' rests against the shoul- dered end F'', but in case a wider filling strip is employed, and the edges of the pans spaced farther apart, then the depending 105 flange A'' would engage one or the other of the slots F''. In order to bring the support- ing arm into operation, the head F' is in- serted in the opening E' and the shank thereof moved up into the narrow portion of 110 said opening thereby lifting the supporting 105

arm to its highest position, and at which point it serves as a support for the pan or form. The hooked end H' of the locking lever is then brought into engagement with the stirrup through the opening E² and the latch I is turned down into engagement with the outer end of the locking lever and the supporting arm will then be securely locked into proper elevated position.

10 When it is desired to remove the form A, so that said form can be used again, the latch I is swung outwardly as shown in dotted lines at the right of Fig. 2 and the locking lever H will drop and the supporting arm F can then be moved down and removed, thereby clearing way for the quick and easy removal of the pan or form without disturbing the wooden supporting members.

20 In case a flat slab pan is employed the head F' of the locking arm will be inserted in the key-hole opening E² and the locking lever will be brought into engagement with the stirrup through the opening E³. When 25 the arm is connected to the stirrup in this manner the upper end thereof will be in substantial alinement with the upper member of the stirrup.

By means of a support constructed as 30 herein shown and described, arched pans or forms can be arranged to provide varying widths of beam structures, and the supports besides providing this variability for beam structures, can also be used in connection 35 with flat slab pans for forming flat ceiling structures.

The stirrup is permanently connected to the joist and the locking lever and latch are permanently connected to the supporting 40 arm and consequently the chance of accidental misplacement of any parts is reduced to a minimum.

The supporting arm can be quickly and easily attached to the stirrup and locked in 45 its elevated position and can also be quickly and easily unlocked and removed when it is

desired to remove the pan or form. All of the parts being made of pressed sheet metal materially reduce the cost of production.

Having thus described my invention, what 50 I claim is:—

1. The combination with a form, of means for supporting said form including a stirrup, a supporting arm adjustable upon said stirrup to either an operative or an inoperative 55 position, together with means for locking said arm in its operative position.

2. The combination with a form, of a stirrup adapted to straddle a stringer, supporting arms adjustable vertically upon said 60 stirrup, locking means carried by said arm and adapted to engage said stirrup.

3. In a device of the kind described, the combination of a stirrup, of supporting arms detachably connected therewith, a locking lever carried by said arms and adapted to engage a stirrup and means carried by 65 said arms for holding said locking levers in engagement with said stirrup.

4. In a device of the kind described, the 70 combination with a stirrup having a plurality of openings in the legs thereof, a locking arm having a plurality of slots in the top thereof and provided with means for engaging the openings in said stirrup, a 75 locking lever carried by each of said arms and a latch carried also by each of said arms and adapted to engage its respective locking lever.

5. In a device of the kind described, the 80 combination with an apertured member of a supporting arm adapted for detachable connection with said slotted member, a locking lever carried by said supporting arm and a latch also carried by said supporting 85 arm, said locking lever being adapted to engage the apertured member and the latch adapted to engage the locking lever.

In testimony whereof I hereunto affix my signature.

RALPH R. LEFFLER.
